UNITED STATES PATENT OFFICE.

FRANS O. ALBERTSON AND GUSTAV OLSEN, OF SIOUX CITY, IOWA, ASSIGNEES TO
ALBERTSON & COMPANY, OF SIOUX CITY, IOWA, A CORPORATION OF IOWA.

ABRASIVE DEVICE.

Application filed August 11, 1927. Serial No. 212,340.

The present invention relates to abrasive devices and is more particularly concerned with abrasive disks and means for supporting the same for rotation.

5 One of the objects of our invention is the provision of a relatively flat abrasive member provided with a simple and effective means of supporting the same for rotation which may be conveniently removed and 10 placed with a minimum loss of time and labor.

Another object of our invention is the provision of an abrasive disk having means on its rear side for removably supporting the 15 same, comprising a plurality of rearwardly projecting tabs secured on said disks and adapted to be received in a slotted supporting wheel and clamped therein to secure the disk for rotation.

20 Another object of our invention is the provision of a durable and economical abrasive disk support comprising an annular felt pad carried by a stamped metal disk or wheel having a cup shaped center flush with the 25 surface of said pad and slotted to receive the supporting tabs of an abrasive disk, which tabs are clamped in said cup by a clamping member threaded on the hub of said stamped wheel.

30 Another object is to provide a means for mounting an abrasive disk on a rotatable support whereby the disk can be quickly removed from the support without removing the support and whereby the rotation of the 35 support helps to keep the disk in fixed position on said support.

Other objects and advantages of our invention will appear more fully from the following description and from the accompanying drawings in which similar characters of reference indicate similar parts throughout the several views.

Referring to the drawings:—

Fig. 1 is a rear elevational view of one 45 modification of the supporting wheel with the clamping member removed.

Fig. 2 is an exploded view of the elements which comprise the supporting wheel and abrasive disk.

50 Fig. 3 is a medial cross-sectional view of the abrasive disk and wheel in assembled relation.

Fig. 4 is a detail cross-sectional view on the lines 4—4 of Fig. 1.

Fig. 5 is a detail view of our abrasive 55 disk with its backing sheet partially broken away.

Fig. 6 is a medial cross-sectional view of a modified form of supporting wheel.

Fig. 7 is a sectional rear view of another 60 modification taken along line 7—7 of Fig. 8.

Fig. 8 is a medial cross section of this embodiment taken along lines 8—8 of Fig. 7.

Fig. 9 is a cross section of this embodiment on lines 9—9 of Fig. 7, illustrating the 65 means for securing the hub to the wheel.

Referring to Fig. 2, 10 indicates in its entirety our supporting wheel and 11 in its entirety our abrasive disk adapted to be carried thereby. The abrasive disk 11 comprises a substantially flat sheet 12 of emery cloth, emery paper, sand paper, or the like, preferably circular in form and adapted to be removably clamped upon the supporting wheel 10.

75 The abrasive disk 11 is provided with a sheet metal plate 13 (Fig. 5) having a plurality of tabs 14 punched out of said plate and the tabs 14 are preferably formed with a rounded end 15 for convenience in guiding them into the slot and to eliminate any sharp corners. The sheet metal plate 13 with its tabs 14 may be made of ordinary tin formed with the tabs projecting at substantially right angles as at Fig. 2, or of 80 resilient sheet metal such as spring brass in which case the tabs are preferably given a slight slant as shown in Fig. 5. The method of attachment in either case is substantially the same except that the tin tabs may be 85 bent over retaining their bent position while the resilient tabs are preferably retained in bent position by a clamping member further to be described. The clamping member may be employed in either case in order to securely clamp the abrasive disk upon the supporting wheel 10.

90 The sheet metal plate 13 is preferably located centrally upon the rear side of the abrasive sheet 12 with its tabs projecting 100 rearwardly and the sheet metal plate may be secured upon the abrasive sheet in many different ways. A convenient and effective method of securing the metal plate upon the abrasive sheet is to provide a backing sheet 105 16 having a plurality of slits 17 located to receive the tabs 14 of the metal plate and the backing sheet may be secured upon the

abrasive sheet with any type of glue or cement, preferably some adhesive which is not affected by the heat generated during the use of the abrasive disk.

5 When the sheets 12 and 16 are severely joined by such an adhesive from the edge of the metal plate 13 to the outer edge of the sheets, the metal plate is securely fixed between the two sheets and the tabs 14 may 10 be employed for fixing the abrasive sheet upon a supporting wheel. In order to make the connection between the metal plate and abrasive disk more durable, cement may also be used between the metal plate 13 and the 15 back of the abrasive sheet 12 and between the metal plate 13 and the backing sheet 16.

The slits 17 as well as the tabs 14 preferably extend radially in order that the tabs may bear against an elongated edge of the 20 slit to increase the bearing surface between these parts in the direction of the rotative forces. However, many of the advantages of our invention may be realized by having the slits and tabs extend in other directions.

25 The supporting wheel 10 comprises a stamped sheet metal disk or wheel 18 of substantially cup shape and having a central flanged aperture 19. The aperture 19 is preferably provided with a flange 20 of substantially cylindrical shape extending to the 30 top of the cup and with a frusto-conical flange 21 extending from the flange 20 to the bottom of the cup. The frusto-conical flange 21 forms a counter sunk portion 22 of the aperture 19 which enables the attachment of a hub 23 without any projecting parts. The disk 18 is also provided with a plurality of radially extending slits 24 of sufficient length to receive the tabs 14 on 35 the abrasive disk 11 and located so that all of the tabs register simultaneously with the slits 24.

The disk 18 is also provided with an annular flange 25 which may be of sufficient 45 width to form a support for a pad 26, or which may be employed with an auxiliary sheet metal plate 27 to support said pad.

In the embodiment shown in Fig. 2, the 50 supporting wheel comprises a cup shaped disk 20 and the sheet metal plate 27 which is riveted thereto by a plurality of rivets 28. The sheet metal plate 27 is a substantially circular plate of metal, preferably of steel, having a centrally located circular aperture 55 29 which is adapted to fit about the wall 30 of the cup shaped disk 18 so that the flange 25 and sheet metal plate 27 may be riveted together. The provision of a sheet metal plate 27 instead of forming the flange 25 of sufficient width to support the pad 26 enables the use of a single size of cup shaped disk with a plurality of different plates 27 to form wheels of different diameters, but we desire it to be understood that these parts 60 65 may be made integral as shown in Fig. 6.

The pad 26 comprises a substantially circular pad of thick felt, preferably of slightly larger size than the metal plate 27 so as to project beyond said plate and pad the exterior edge of the plate as well. The pad 70 26 is of sufficient thickness so that the external surface 31 of the cup shaped disk is substantially flush with the top of the pad. The pad may be affixed to the backing wheel by a plurality of rivets 32 passing through 75 aligned apertures in the plate 27 and the pad 26 and riveted over small washers 33. The washers should preferably be riveted down into the felt pad compressing the pad about the rivet so that the top of the rivet is flush with the surface of the pad or below the same and the pad has no projecting parts.

The hub 23 comprises a tubular member preferably formed of steel which is internally threaded as at 34 for the reception of the threaded end 35 of an arbor 36 which is adapted to rotate the abrasive wheel. The hub 23 is also provided with an externally threaded surface 37 adapted to receive an internally threaded clamping member 38, and the hub 23 is originally formed as shown in Fig. 2 with a reduced end 39 of substantially cylindrical form adapted to fit within the aperture 19. The reduced end forms an annular shoulder 40 which may bear against the upper edge of the annular flange 20, and the lower edge 41 of the hub may be spun outward within the counter sunk aperture 22 to the dotted line position shown in Fig. 2, thereby permanently assembling these parts together. The cup shaped disk 18 will then be firmly held upon the hub being engaged between the shoulder 40 and the outwardly spun frusto-conical flange 42 as shown in Fig. 6.

100 The clamping member 38 comprises a substantially cylindrical metal member, preferably of steel, having a centrally located bore 43 adapted to pass the arbor 36 and its threaded end 35, and having a threaded counter bore 44 which is complementary to the threaded portion 37 of the hub. The clamping member may be provided with an enlarged counter bore 45 communicating with the threaded counter bore 44 by a frusto-conical surface 46 in order that the lower portion of the aperture in the clamping member may be of sufficient size to receive the flanges 20 and 21 about the hub. The clamping member 38 is also provided with an annular flange 47 projecting from its lower end at substantially right angles to the axis of the bores and forming a lower smooth clamping surface 48 having a substantially circular boundary 49.

105 110 115 120 125 130 The flange 47 is adapted to fit within the annular recess 50 of the cup shaped member 18 when in clamping position. The clamping member 38 may also be provided with a smaller bore 51 extending into the clamping

member from its cylindrical outer surface in a direction at right angles to the axis of the bores, for the reception of a peg or other form of tightening wrench.

5 In the modification shown in Fig. 6 the flanges 25 of the cup shaped disk 18 is of sufficient width to support the pad 26 without an auxiliary sheet metal plate 27. The other details of these two devices may be 10 exactly the same.

In the modification shown in Figs. 7, 8 and 9, the hub 23' is secured to the wheel by a riveted flange 51 instead of by a frusto-conical flange and the clamping member 15 38 is entirely dispensed with. The wheel 18' is provided with a central aperture 19' which snugly fits the end of the hub 52. The hub is provided with a star shaped flange 51, as shown in Fig. 7, so that it may 20 be secured to the wheel by rivets 53 without interfering with the slots 24. This is clearly shown in Fig. 9.

The operation and assembly of the abrasive wheel and disk illustrated in Figs. 1 to 25 6 is as follows. The clamping member 38 is first placed upon an arbor 36 with the flange 47 toward the outer end of the arbor, after which the hub 23 of the wheel may be threaded upon the threaded end 35 of the 30 arbor to the end of the thread where these two parts become fixed together. The wheel may then be provided with an abrasive disk of the form shown in Figs. 2 or 5, the tabs 14 being passed through the slots 35 24 in the wheel. The tabs 14 may then be bent over on the other side of the slots within the annular space 50 and the clamping member 38 threaded upon the hub until the 40 surface 48 clamps the ends of the tabs 14 against the bottom of the cup.

Another method of attachment where the tabs 14 are resilient would be to pass the tabs through the slits 24 and pressing upon the abrasive disk so as to hold it tightly 45 against the wheel the clamping member 38 may be threaded home in such manner that the flange 47 will bend the tabs 14 over, clamping these tabs in the same way.

The operation of the modification shown 50 in Figs. 7 to 9 is still more simple. In this case the tabs 14 are of heavier metal than in the former case and they do not require a clamping means. Heavy tin tabs inserted 55 through the slots and bent over will hold the disk securely without the clamping device. Tabs of material too resilient to retain this bent position are held in place by the rotation of the wheel; the wheel in rotating causes the edges of the slot to exert 60 force against the slanting tabs, and one component of this force tends to hold the disk on the wheel.

While the preferred embodiment has been 65 described as using metal tabs, it is understood that any material may be used which

has the necessary physical properties. Sheets of cellulose compounds, condensation products, fiber compositions, etc., may be used instead of sheet metal as long as the tabs punched from these sheets are rigid and 70 strong enough to hold the disks in place. Also the backing paper itself may be made of a sheet of strong fiber composition or the like and may be provided with tabs for engaging the slots of the support, thus eliminating the metal sheet altogether. Many 75 other modifications will be evident to those skilled in the art without departing from the spirit of our invention.

It will be observed that we have provided 80 an abrasive disk, and a novel supporting wheel, these parts having a simple and effective means for removably supporting the disk upon the wheel. Our abrasive disk may be removed with a minimum expenditure of time and labor, and by the use of our supporting means the central portion of the disk is preserved for grinding at relatively low speeds. The clamping member 85 38 cannot become lost or detached because 90 when it is not in clamping relation it is retained loosely upon the arbor 36. If desired the clamping member 38 may be provided with an exterior surface which is noncircular, such as hexagonal, to receive an ordinary wrench instead of having the bore 51.

While we have illustrated and described a specific embodiment of our invention, many modifications may be made without departing from the spirit of the invention, 100 and we do not wish to be limited to the precise details of construction set forth, but desire to avail ourselves of all changes within the scope of the appended claims.

Having thus described our invention, what 105 we claim as new and desire to secure by Letters Patent of the United States is:

1. In an abrasive device, the combination of a sheet metal wheel having a cup formed therein, an annular pad carried by said wheel flush with the outside of said cup, said cup having a plurality of radial slots, and a 110 tubular hub having a reduced end passing through said cup and spun outwardly to secure the same to said disk.

2. In an abrasive device, the combination of a sheet metal wheel having a cup formed therein, an annular pad carried by said disk flush with the outside of said cup, said cup having a plurality of radial slots, and a 120 tubular hub having a reduced end passing through said cup and spun outwardly to secure the same to said disk, said hub being threaded to receive a clamping member comprising an internally threaded sleeve with an 125 annular flange receivable in said cup.

3. In an abrasive device, the combination of a sheet metal disk having a flanged counter-sunk aperture at its center, a felt pad carried by said disk, and a hub comprising 130

a sleeve having a reduced end to be received in said aperture, said end being spun outward in said counter-sunk aperture.

4. In an abrasive device, the combination of a sheet metal disk having a flanged counter-sunk aperture at its center, a felt pad carried by said disk, a hub comprising a sleeve having a reduced end to be received in said aperture, said end being spun outward in said counter-sunk aperture, said disk having a plurality of slots for receiving projecting tabs of an abrasive member, and a clamping member threaded on said hub to clamp said tabs.

5. In combination, a wheel provided with a cup shaped disk having radial slots, an annular flange on said disk, a supporting pad on said flange, an abrasive disk adapted to fit against said supporting pad, tabs extending from the back of said disk and spaced to register in said slots whereby the abrasive disk may easily be put on or removed. 15

In witness whereof, we hereunto subscribe our names this 6 day of August, 1927.

FRANS O. ALBERTSON.
GUSTAV OLSEN.
